UNITED STATES PATENT OFFICE.

DARWIN J. PARMELE, OF CHICAGO, ILLINOIS.

IMPROVEMENT IN GUIDE-FRAMES FOR SAWS.

Specification forming part of Letters Patent No. **148,136**, dated March 3, 1874; application filed December 20, 1873.

To all whom it may concern:

Be it known that I, DARWIN J. PARMELE, of Chicago, Cook county and State of Illinois, have invented a new and Improved Guide-Frame for Saws, of which the following is a specification:

In the accompanying drawing, Figure 1 represents a side elevation of my improved hand-saw guide-frame; Fig. 2, a bottom view; and Fig. 3, a vertical transverse section of the same on the line *c c*, Fig. 2.

Similar letters of reference indicate corresponding parts.

My invention relates to a simple and convenient guide-frame for adjusting saws for cutting at various depths; and consists in a slotted frame with suitable handles, into which the saw-blade is set, so as to project at the required depth below the bottom part, being firmly clamped by strong tightening-screws.

In the drawing, *A* represents the guide-frame, in which a saw-blade, *B*, of the usual kind used by carpenters, stair-builders, and others, is inserted. Frame *A* may be made of wood, in one piece, with the handles *C*, and is, in that case, provided with metallic base-strips *a*, which are attached by countersunk screws to the lower edge of the frame at both sides of the vertical longitudinal slot or recess *b*. Frame *A* may be made also of iron or other metal, dispensing with strips *a*, being attached to the handle in a suitable manner. Slot *c*

extends centrally through the whole length of frame *A*, and to some distance from the top part, and serves to take up the saw-blade *B* therein. Screw-bolts *D*, with tightening-nuts *D'*, are applied at both ends of frame *A*, near the lower corners thereof, for clamping the sections of the frame firmly on blade *B*, after the same has been adjusted to the depth required to be sawed. The blade *B* is firmly held along its full length by the lower parts of frame *A*, and readily changed to different depths by loosening the screw-nuts, resetting the blade, and tightening the nuts again. A new blade may also be inserted, or blades of different cut of teeth, forming thereby a convenient and useful implement for the trades.

Having thus described my invention, I claim as new and desire to secure by Letters Patent—

The saw frame or holder herein described, consisting of the slotted body *A*, having handles *C*, and adapted for the reception of a detachable saw-blade, *B*, which is retained in position by clamping-bolts *D* passing through the ends of the frame or holder, all constructed and arranged as herein shown and set forth.

DARWIN JOHN PARMELE.
